UNITED STATES PATENT OFFICE.

GEORGE WATKINSON, OF NEW HAVEN, CONNECTICUT.

DESIGN FOR ORNAMENTATION OF OVERSHOES.

SPECIFICATION forming part of Design No. 14,372, dated October 23, 1883.

Application filed May 31, 1883. Term of patent 14 years.

To all whom it may concern:

Be it known that I, GEORGE WATKINSON, of New Haven, in the county of New Haven and State of Connecticut, have invented a new 5 Design for Ornamentation of Overshoes; and I do hereby declare the following, when taken in connection with accompanying drawing and the letters of reference marked thereon, to be a full, clear, and exact description of the same, 10 and which said drawing constitutes part of this specification, and represents a top view.

This invention relates to a design for the ornamentation of that class of overshoes which present an india-rubber surface; and it consists in the representation of bands running diagonally over the vamp, those running from one side crossing those coming from the opposite direction and forming diamond-shaped spaces on the surface, and as more fully here- 15 after described.

The general outline of the upper may be any of the usual shapes, that being immaterial to

this design. On the vamp is the representation of bands running from each side near the sole over the vamp to the opposite side, those 25 coming from one side crossing those coming from the opposite side, and forming diamond-shaped spaces, as shown in the accompanying illustration. These bands may be plain, as shown, or ornamented, without departing from 30 this design, the essential feature of which is the crossing diagonal bands on the vamp portion of an india-rubber shoe.

I claim—

The design for the ornamentation of india- 35 rubber overshoes, consisting in the representation of diagonal bands over the vamp portion, those running in one direction crossing those running in the opposite direction, as shown in the accompanying illustration.

GEO. WATKINSON.
